George C. Mayer

INVENTOR
MAX DOBRIN,

BY *u*

Munro & Co
ATTORNEYS

UNITED STATES PATENT OFFICE.

MAX DOBRIN, OF DENVER, COLORADO.

VALVE.

Original application filed July 14, 1921, Serial No. 484,732. Divided and this application filed September 14, 1922. Serial No. 588,234.

To all whom it may concern:

Be it known that I, MAX DOBRIN, a citizen of the United States, and a resident of Denver, in the county of Denver and State 5 of Colorado, have invented certain new and useful Improvements in Valves, of which the following is a specification.

This invention relates to improvements in valves.

10 The present application is a division of my pending application for patent on dispensing device for liquids, Serial No. 484,732, filed July 14, 1921.

15 The object of the invention is to provide a valve which serves to efficiently control the flow of liquid through an orifice or an opening and adapted to be extremely easy to operate.

20 It is a further object of the invention that the valve be adapted to operate for controlling an opening within a nipple or other enclosure.

25 Other objects will hereinafter appear in the detailed description to follow.

20 The invention is illustrated by way of example in the accompanying drawings, in which:—

30 Figure 1 is a detailed sectional view of a tank with nipples extending therefrom and showing the application of the valve employing the present invention.

35 Figure 2 is an enlarged detailed view further illustrating the construction of the valve and the manner in which the same may be mounted for controlling the flow of liquid through an orifice or opening.

40 Referring to the drawings, D generally indicates a drum or container which may be filled with a liquid. The drum may be formed with a plurality of nipples N, each nipple having its inner end formed with a closure 10, and said closure having a central orifice 11 adapted to establish communication between nipple and the interior 45 of the drum D. Each nipple may be threaded at its outer end as at 12 and threaded to a tubular extension 13. In the parent application heretofore referred to the tubular extensions 13 50 each terminate at its outer end in a mouth-piece which may be pressed to a person's mouth for drinking liquid emitted or discharged from the drum D.

55 Each of the nipples N is provided with a valve for controlling the flow of liquid

through the associated orifice 11. An arm or prong 14 is preferably formed upon an outer wall of the nipple N and has its inner end terminating in an enlargement 15. The enlargement 15 is provided with a suitable transverse opening for receiving the pin or rivet 16 whereby to fulcrum a substantially L-shaped lever 17. The lever 17 consists of the two portions 18 and 19 disposed at substantially right angles to each other, and the pin or rivet 16 passing through the portion 19 at a point adjacent its inner end as illustrated to advantage in the drawings. The portion 18 of the lever 17 terminates at its free end in a closure 70 plate or valve 20 which is adapted to seat over the orifice or opening 11 of the associated nipple. The arm or prong 14 is provided adjacent its outer end with a pair of posts or studs 21, each of which is adapted to pass through a suitable opening in the associated end of the lever portion 19. A coiled spring 22 encircles each of the studs 21, said coiled spring being interposed between the lever arm 19 and the arm or prong 14. The lever arm 19 is also formed with a vertically disposed extending flange 23 along its one edge adapted to hold the lever 17 against lateral movement when brought to its position for removing the 85 closure plate 20 from the orifice 11.

As is obvious from the description heretofore given of the drawings accompanying the present application, the lever 17 may be operated for opening the orifice 11 by 90 pressing the lever portion 19 upon the prong or arm 14 against the tension of the springs 22. The springs 22 tend to normally retain the lever in position for closing the orifice 11 of the associated nipple N.

95 While I have shown my valve serving a certain use and mounted in the particular manner, it is to be understood, that I am aware of the fact that minor changes may be made in the valve for serving other similar purposes without departing from the spirit of the invention as indicated by the appended claims.

I claim:—

100 1. In a device of the character described, a container, a nipple communicating with the interior of the container through an orifice, a lever fulcrumed in the wall of the nipple and extending transversely to the passage of said nipple, said lever carrying 110

on its inner end a valve member adapted to close the orifice of the nipple and on its outer end formed with a handle adapted for manipulating the same for opening and closing said orifice.

2. In combination, a container, a nipple extending from the container and communicating with said container through an orifice, a lever fulcrumed upon said nipple and having a portion operable within the walls of said nipple, said portion being provided with a head for forming a closure for said nipple when brought into seating engagement with the wall surrounding said orifice.

15 3. In combination, a container, a nipple extending from the container and communicating with said container through an orifice, a lever fulcrumed upon said nipple and having a portion operable within the walls of said nipple, said portion being provided with a head for forming a closure for said nipple when brought into seating engagement with the wall surrounding said orifice, and means for normally and yieldably pressing said lever for closing the orifice.

4. In combination, a container, a nipple extending from the container and communicating with said container through an orifice, a lever fulcrumed upon said nipple and having a portion operable within the walls of said nipple, said portion being provided with a head for forming a closure for said nipple when brought into seating engagement with the wall surrounding said orifice, and spring means for normally and yieldably pressing said lever portion for closing said orifice.

5. In combination, a container, a tubular member communicating with said container through an orifice, a lever fulcrumed upon

said tubular member and having a portion thereof disposed within the tubular member and adapted to be brought in position for closing said orifice.

45 6. In combination, a container, a tubular member communicating at one end through an orifice with said container, an arm extending from the outer surface of the tubular member, and a lever fulcrumed upon said arm and having a portion extending within the tubular member carrying a head adapted to form a closure for said orifice.

7. In combination, a container, a tubular member communicating at one end through an orifice with said container, an arm extending from the outer surface of the tubular member, a lever fulcrumed upon said arm and having a portion extending within the tubular member carrying a head adapted to form a closure for said orifice, and spring means interposed between the outer end of the lever and the arm extending from said tubular member whereby the lever may be normally maintained in a position for closing said orifice.

60 8. In combination, a container, a tubular member communicating at one end through an orifice with said container, an arm extending from the outer surface of the tubular member, a lever fulcrumed upon said arm and having a portion extending within the tubular member carrying a head adapted to form a closure for said orifice, spring means interposed between the outer end of 70 the lever and the arm extending from said tubular member whereby the lever may be normally maintained in a position for closing said orifice, and means associated with said arm and lever whereby to prevent lateral movement of the lever.

75 80 MAX DOBRIN.
